UNITED STATES PATENT OFFICE.

FRANKLIN ADELBERT TERRY, OF SAN FRANCISCO, CALIFORNIA.

AUTOMATIC BURGLAR-ALARM.

1,350,188.

Specification of Letters Patent. Patented Aug. 17, 1920.

Application filed July 9, 1917. Serial No. 179,378.

To all whom it may concern:

Be it known that I, FRANKLIN ADELBERT TERRY, a citizen of the United States, and a resident of San Francisco, in the county 5 of San Francisco and State of California, have invented an Improvement in Automatic Burglar-Alarms, of which the following is a specification.

My invention relates to improvements in 10 automatic burglar alarms, and it consists in the constructions, combinations and arrangements herein described and claimed.

An object of my invention is to provide 15 a burglar alarm which will send in a call for help over a telephone whenever the device is put into operation. In the present instance, I have shown manual means for starting the device which thereupon operates automatically, but it is obvious that 20 push buttons might be arranged to start the device upon the opening of a window or a door, without departing from the spirit of the invention.

My invention is illustrated in the accompanying drawings, forming part of this application, in which—

Figure 1 is a side view of the device connected up with a telephone.

Fig. 2 is a plan view, certain parts being 30 removed for the sake of clearness.

Fig. 3 is an enlarged section on the line 3—3 of Fig. 2.

Fig. 4 is a perspective view of a spring suspending means.

Fig. 5 is a perspective view showing the arrangement of levers for controlling the device.

Fig. 6 is a diagrammatic view of the electric circuit.

In carrying out my invention, I may 40 make use of a phonograph of any approved type, such as a cylinder phonograph. In the drawings the base of the phonograph is shown at 1, cylinder at 2, the traveling arm at 3, and the sound reproducing mechanism carried thereby at 4. The cylinder is preferably provided with recorded calls which are repeated at intervals, these calls being such as "Send the police to 126 McAllis- 45 ter street," or similar calls.

Normally, that is to say when the instrument is set, the diaphragm of the reproducing mechanism rests with its edge on a spring support 5 like that shown in Fig. 4, 55 this spring support being secured to the casting of the device. The purpose of this support is to raise the needle from the wax cyl-

inder, since the latter, in warm weather, is apt to permit the needle to sink in to such a distance that it is difficult to start the 60 machine.

In connection with the phonograph I make use of a motor M whose shaft is provided with an L-shaped arm 6. This arm is arranged to engage a lever 7 which is pivoted at 8 and whose end is bent as shown at 9 to engage a brake lever 10.

As will be seen from the drawings, and especially Fig. 5, I provide a lever 11 which is pivoted at 12 and whose opposite end is 70 bent into U-shaped form, as shown at 13. The portion 13 is provided with a slot 14 through which the brake lever extends. The end of the portion 13 is curved upwardly and rearwardly, as shown at 15, so 75 as to permit the hook 9 on the end of the lever 7 to ride over the upper end of the brake lever to engage the latter, in the manner hereinafter described.

Secured to the lever 1 is an L-shaped arm 80 16 having a slot 17 arranged to straddle the screw shaft 18, see Fig. 2, which forms the driving means for the movable arm 3.

Associated with the phonograph is a telephone set, this set being preferably a desk 85 set. In order to conveniently mount the same I provide a stand or taboret 20 to which the desk set is firmly clamped. At 21 is a bracket bearing a bell crank lever 22, one end of this bell crank lever being attached, by means of a link or other suitable connection 23, to the switch hook 24 of the telephone set. The other arm of the lever is attached to the U-shaped portion 13 of the lever 11.

From the foregoing description of the various parts of the device the operation thereof may be readily understood. The motor M is connected with the battery B, and the push buttons P or P' may be used 100 to close the motor circuit when the switch S is in the position shown in Fig. 6. This circuit may be closed in any suitable way, such as by operating it manually, that is to say pressing the push button with the hand, or closing it by the opening of a window or in any other suitable manner.

In setting the device the phonograph is wound up and the brake lever 10 is moved in position to prevent the operation of the 110 phonograph, the lever 7 being brought over the end of the brake lever 10 to hold the latter, as shown in Fig. 1. The movement of the lever 10 will cause the switch hook 24

to be pulled downwardly where it will be held against the tension of the switch hook spring, precisely as if the receiver were hanging on the hook. The diaphragm of the reproducer is resting on the spring support 5.

Now if the circuit is closed by pressing the push buttons the motor M will turn and the arm 6 will engage the lever 7, raising the 10 end 9 off from the brake lever 10 whereupon the latter will be released and the machine started. At the same time the switch hook 24 will move to its upper position so as to complete the talking circuit of the telephone. The movement of machine moves the arm 3 away from the support 5 and brings the needle of the reproducer into engagement with the cylinder bearing the recorded calls. These are now sent in through 15 the medium of the tube 28, and the sound amplifier 29, the latter being supported by 20 means of a bracket or post 30 in front of the transmitter T of the telephone.

The device will continue to repeat the calls 25 until the hub 3^x of the arm 3 engages the arm 16, whereupon the lever 11 will be moved to the position shown in Fig. 1, the hook 9 will be brought into engagement with the upper end of the lever 10, so as to retain 30 it in position, and the switch hook of the telephone will be again drawn downwardly.

I claim:

1. A burglar alarm comprising a telephone set, a phonograph disposed near the set, a brake for normally holding the phonograph mechanism stationary against spring tension, means connecting the switch hook of the telephone set with the brake mechanism for holding the switch hook in normal position, a motor, an electric circuit for operating the motor containing circuit closing devices, a locking lever for holding the said brake lever in position to prevent the operation of the phonograph, connections between 35 said motor and said locking lever for releasing the latter and thereby permitting the operation of the phonograph, and the releasing of the switch hook to bring it into position to complete the talking circuit, and 40 means for automatically resetting the brake and the switch hook, when the alarm has been sent in.

2. A burglar alarm comprising a telephone set, a phonograph disposed near the set, a 45 brake for normally holding the phonograph mechanism stationary against spring tension, means connecting the switch hook of the telephone set with the brake mechanism for holding the switch hook in normal position, a motor, an electric circuit for operating 50 the motor containing circuit closing devices, means for holding the phonograph needle normally out of engagement with the record, means actuated by the motor for releasing the brake mechanism and the 55

switch hook, and means for subsequently shifting the needle holding means to permit the needle to be brought into operative engagement with the record.

3. A burglar alarm comprising a telephone 70 set, a phonograph disposed near the set, a brake for normally holding the phonograph mechanism stationary against spring tension, means connecting the switch hook of the telephone set with the brake mechanism 75 for holding the switch hook in normal position, a motor, an electric circuit for operating the motor containing circuit closing devices, means for holding the phonograph needle normally out of engagement with the record, means actuated by the motor for releasing the brake mechanism and the switch hook, means for subsequently shifting the needle holding means to permit the needle to be brought into operative engagement 80 with the record, and means for automatically applying the brake when the alarm has been sent in.

4. A burglar alarm comprising a telephone set, a phonograph disposed near the set, a 90 brake for normally holding the phonograph mechanism stationary against spring tension, means connecting the switch hook of the telephone set with the brake mechanism for holding the switch hook in normal position, a motor, an electric circuit for operating 95 the motor containing circuit closing devices, means for holding the phonograph needle normally out of engagement with the record, means actuated by the motor for releasing the brake mechanism and the switch hook, means for subsequently shifting the needle holding means to permit the needle to be brought into operative engagement 100 with the record, means for automatically applying the brake when the alarm has been sent in, and for restoring the switch hook to its normal position.

5. A burglar alarm comprising a telephone set, a phonograph disposed near the set, a 110 brake for holding the phonograph mechanism stationary against spring tension, means connecting the switch hook of the telephone set with the brake mechanism for holding the switch hook in normal position, 115 a motor, an electric circuit for operating the motor containing circuit closing devices, a support secured to the casing of the phonograph for manually holding a needle out of engagement with the record, the movement 120 of the reproducer which bears the needle serving to bring the needle into operative engagement with the record, and means actuated by the motor for simultaneously releasing the brake mechanism and the 125 switch hook.

FRANKLIN ADELBERT TERRY.
